UNITED STATES PATENT OFFICE.

LEO FRIEDRICH HERRMANN, OF VIENNA, AUSTRIA-HUNGARY.

DOOR.

SPECIFICATION forming part of Letters Patent No. 577,657, dated February 23, 1897.

Application filed May 22, 1896. Serial No. 592,558. (No model.)

To all whom it may concern:

Be it known that I, LEO FRIEDRICH HERRMANN, a subject of the Emperor of Austria-Hungary, residing at Vienna, in the Province 5 of Lower Austria, in the Empire of Austria-Hungary, have invented certain new and useful Improvements in Doors Adapted to be Opened on Both Sides, of which the following is a specification.

10 This invention relates to an improved door adapted to be opened from both sides, and has special reference to car-doors. Heretofore doors of this kind have been constructed with very complicated mechanisms for disengaging the hinges, which made these doors too expensive.

15 My invention provides an improved door which is cheap and simple in construction. It is the special object of the same to furnish 20 a door in which the disengaging of the hinges on the one side is effected while simultaneously the hinges on the other side are secured by aid of a simple lock mechanism and by means of a simple lever work which prevents 25 the door from falling out.

20 My improved mechanism may be applied to any kind or style of doors. The accompanying drawings illustrate a car-door.

Figure 1 shows an elevation of the mechanism, partly in section. Fig. 2 is a horizontal sectional view. Fig. 3 is a cross-section. Figs. 4 to 8 represent the left upper hinge with securing device in several views and sections, and Fig. 9 is a plan view of the left upper hinge.

25 The drawings clearly illustrate that the mechanism consists of three essential parts—the hinges adapted to be disengaged, the door-handle with the lock mechanism, and 30 the lever work with springs. The main parts of the construction are the hinges, which are easily disengaged. Each door is provided with four hinges, two of which are symmetrically constructed. They are situated at 35 equal height on both sides of the door.

40 The mechanism on each side of the door is the same, and therefore I will describe it on one side only.

45 The hinges consist of three parts, the pivot-journals a, a^2 , which are mounted on the door-post, the guiding-sockets b, b^2 , attached to the door, and the hinge-pivots d, d^2 , carried

5 by lugs c, c^2 . The lugs c, c^2 of the hinges on the one side of the door are mounted on a common rod or bolt f , adapted to slide in 55 a groove near the beating-bracket e of the door, which rod is actuated by the lock mechanism. The bolt f is operated in such a manner that a cam h^2 of the handle-piece h , actuated by the handle k , engages into a recess 60 f^2 in the bolt f , so that by pressing down the handle k the bolt or rod f is lifted, and simultaneously with this rod are moved upward the lugs c, c^2 , carrying with them the hinge-pivots d, d^2 and lifting the same out from the 65 journals a, a^2 , so that the door may now be turned about the pivots of the other side. After releasing the handle k the bolt or rod f returns to its original position by means of a spiral spring m , which is provided above 70 the lug c . The spring m surrounds the bolt or rod f .

75 In order to make it unnecessary to operate the handle again when closing the door, the hinge-journals a, a^2 are extended forward and are provided with an inclined sliding-surface n, n^2 , on which, while the door is closing, the hinge-bolts d, d^2 move upward and snap into the bores of the hinge-journals when the door is perfectly closed.

80 It is further necessary to prevent the hinges from being disengaged simultaneously on both sides, which would result in lifting the door therefrom. This might happen when two persons operate the handles each on one side 85 of the door at the same time, or when the door is not yet perfectly closed the hinges on the other side could be disengaged, or when the door might be opened purposely on both sides. In order to prevent these accidents, 90 the trigger-nuts of both locks are connected by lever k^2 and by a common bolt p , provided in a groove of the door, so that when the one handle is pressed down the other handle is moved up.

95 When both handles are moved simultaneously, the bolt p ought to move in both directions, but that is impossible and none of the handles can be operated until one is released.

100 When the door is nearly closed from one side, the hinge-pivots of this side are on the highest point of the inclined surface, but they have not yet snapped into their journals. Then the bolt or rod f is lifted, while the other

bolt or rod is secured against moving upward owing to the lower position of the cam h^2 , caused by bolt p , whereby it is effected that the opposite handle is secured or locked. 5 Further, it may happen that the door is not closed enough for bringing the pivots in contact with their journals, a position shown in full lines in Fig. 7. To prevent accident in this instance, each of the upper journals a^1 10 is provided with a snapping device $q^1 q^2$, that is a double-armed lever with shanks of different length. This lever turns on a fulcrum q^3 and is provided with a tooth-like piece q^4 , which fits into a recess r^2 of a disk r , Fig. 9. 15 The disk is fixed to the lever c or is integral therewith, so that by turning the door on one of the hinges by the oscillation of the disk r the snapping device q is closed. Hereby the portion on the inner side of the journal a 20 rises above a wedge-like projection c^4 of lug c and thus prevents the latter being raised.

By completely opening the door, as shown in Fig. 7 in dotted lines, the wedge c^4 slides below the snapping device q . Therefore I 25 have made the arrangement so that the enlarged lug c , which carries the upper hinge-pivot d , may enter into a recess a^5 in the hinge-journal a pertaining thereto before the wedge-like part c^4 leaves the snapping device q , whereby the one hinge is prevented 30 from being disengaged, provided the door be opened.

An occasional motion of the pivoted snapping-stop q may effect, when the door is 35 opened, a clamping or pinching of the hinges by the closing operation. To prevent this the pivoted stop q is limited in its oscillation on the one side by the wall of the journal and on the other side by a pin s . The stop q is brought to 40 its normal position by the projection on disk r . Thus any harmfully-intended operation of the device is made very difficult, the more since the single volute spring m is located in a recess of the door and is covered by a plate t , Fig. 8, which is integral with the lever c . 45

The door, further, may be protected against lifting it from the hinges by a bar closely above the same. In order to render it possible that the door may be used as a one-sided 50 door, each lock is provided with an arresting device composed of a key v , which is adapted to be laid down and which may be maintained in two positions by spring u . This key when turned upward, as shown in Fig. 1, central 55 left view, engages below a cam w of the trigger-nut h and prevents these from turning.

The size of the different detail parts may be varied at will without departing from my invention.

60 Having now described my invention, what I claim therein as new, and desire to secure by Letters Patent, is—

1. In a door adapted to be opened on both sides the combination of the door with disengaging hinges on both sides above and below,

65 pivot-journals on the door-post, rods sliding in grooves provided in the edges of the door and having lugs projecting laterally therefrom beyond the edges of the door carrying pintles which engage the pivot-journals of the 70 door-post, said rods being actuated vertically by the locking mechanism to release the pintles when the door is opened, substantially as described.

2. In a door adapted to be opened on both 75 sides the disengaging hinges consisting of the pivot-journals mounted on the door-post, the guiding-sockets attached to the door and the hinge-pivots carried by lugs which project laterally from the sliding bars in combination 80 with a rod having a slot in which engages a cam actuated by the door-handle which by being pressed down lifts the rod carrying with it the hinge-pivots and lifting them from their journals so that the door may now turn about 85 the pivots on the other side, substantially as described.

3. In a door adapted to be opened on both 90 sides the combination of the disengaging hinges with pivot-journals on the door-post, rods sliding in grooves provided in the edges of the door and having projecting lugs with extensions, a notch-disk formed integral with the projecting lugs, pintles dependent of the rod and a snapping-stop pivoted to the frame 95 of the pivot-journal with teeth engaging the notch of the disk, so that by turning the door on one of the hinges the notch-disk oscillates and swings the pivoted stop over the lug extension thus preventing the bar from lifting, 100 substantially as described.

4. In a door adapted to be opened on both 105 sides the combination of the disengaging hinges with a rod having a projecting lug with extension and a slot in which engages a cam actuated by the door-handle which by being pressed down lifts the rod and the lug carrying with it the hinge-pivots and lifting them from their journals, and a spiral spring surrounding the rod which returns the rod to its 110 original position after the handle is released, substantially as described.

5. In a door adapted to be opened on both 115 sides the combination of the disengaging hinges with rods sliding in grooves on the edges of the door and having projecting lugs which carry pintles, hinge-journals on the door-post which extend forward and are provided with inclined surfaces on which the pintles move upward while the door is closing 120 and past which they snap into the bores of the journals when the door is perfectly closed, substantially as described.

In testimony whereof I have signed this specification in presence of two subscribing 125 witnesses.

LEO FRIEDRICH HERRMANN.
